By Byron Townsend & Brickstone,
Attorneys.

UNITED STATES PATENT OFFICE.

EUGEN HENKEL, OF FRANKFORT-ON-THE-MAIN, GERMANY, ASSIGNOR TO METALL-BANK UND METALLURGISCHE GESELLSCHAFT, AKTIENGESELLSCHAFT, OF FRANKFORT-ON-THE-MAIN, GERMANY, A CORPORATION OF GERMANY.

HARDNESS-TESTING MACHINE.

Application filed January 17, 1923. Serial No. 613,301.

To all whom it may concern:

Be it known that I, EUGEN HENKEL, engineer, a citizen of the German Republic, and residing at Rodelheimerlandstrasse 72, 5 Frankfort-on-the-Main, Germany, have invented certain new and useful Improvements in Hardness-Testing Machines, of which the following is a specification.

The present invention relates to a hardness-testing machine of the Brinell type, 10 which contrary to the devices known up to now for this purpose combines the advantages of simple construction with that of great precision of the test results.

15 To this end the pressure is applied in the known manner by a weight-operated lever and adapted to be slowly and regularly transmitted to a die carrying at one of its ends the pressure ball.

20 According to the present invention the transmission of pressure is effected by the arrangement that the support on which the lever presses when in resting position can be lowered and raised for instance by means 25 of an eccentric. Owing to the fact that by means of a spring the stamp is pressed continuously against the lever, and that the material to be tested lying on a table can be adjusted by means of a male screw so as to 30 come into immediate contact with the ball, uniform load of the ball without shocks is obtained as soon as the eccentric upon which the lever rests is lowered. Thereby most 35 precise results can be obtained with even such simple and cheap device.

In the accompanying drawings which show by way of example one form of execution of the invention,

Fig. 1 is a front elevation, partly in section, of a testing machine, and

Fig. 2 is a vertical section through the load transferring mechanism.

On a casing 1 of any construction there is arranged a lever 2 turning on the edge 4 and provided at one of its ends with the weight 3. The lever is resting on the eccentric 5, which may be operated by means of a second lever 6 and is adapted so as to have in its resting position the full eccentricity above the centrepoint. The die 7 is guided by a shell 8 rigidly connected with the casing. Between the bottom end

of the shell and a collar 9 encircling the die a spring 10 is arranged in such a way as to press the die continuously against the lever arm. The ball 11 is interchangeably connected to the bottom end of the die 7. It is advisable to also provide the top end of the die in touch with the lever in the same manner with a similar ball 12. The material 13 to be tested lies on the table 14, which by means of the screw spindle 15 can be raised and lowered. By means of a water level 16 the machine can be arranged in such a way as to give the stamp 7 a vertical position. To execute the test the table with the material to be tested is raised until the latter comes into contact with the ball 11. Thereby care must be taken that the surface of the material to be tested upon which presses the ball 11 be in a horizontal position. By means of the lever 6 the eccentric 5 is now given a slow and regular rotation so that the pressure of the weight 3 is transferred to the ball 11 by means of the lever 2 and the stamp 7. When the ball has acted upon the material for a predetermined time, the eccentric is turned back whereby the lever 2 is raised. Simultaneously the spring 10 causes the die 7 to raise whereby the ball 11 is lifted from the depression, thus releasing the material to be tested. The latter now can be removed from the table to determine the depression and the machine is again ready for use.

To prevent during the testing operation any other movement of the lever 2 than that prescribed the machine can be fitted with such devices as are known for this purpose.

The pressure to be effected by the ball on the material can be increased or decreased by replacing the weight or by changing the transmission ratio.

What I claim is:

1. In a hardness-testing machine, a die, means for guiding said die, a weight-operated lever, and a ball on the upper end of said die for engaging said lever.
2. In a hardness-testing machine, a die, means for guiding said die, a weight-operated lever, and a spring urging the upper end of said die towards said lever.
3. In a hardness-testing machine, a die,

a sleeve for guiding said die vertically, a weight-operated lever, a ball on the upper end of said die, and a spring pressing said ball against said lever.

5 4. In a hardness-testing machine, a die, a weight-operated lever, an eccentric for supporting said lever and adapted to be lowered

and raised for loading and unloading said die with the pressure of said lever, a ball between said die and lever, and a spring 10 urging said die upwardly.

In testimony whereof I affix my signature.

EUGEN HENKEL.
